W. H. DIFFENDALL,
MACHINE FOR HOLDING RIVETS DURING UPSETTING,
APPLICATION FILED MAR. 28, 1917.

1,247,380.

Patented Nov. 20, 1917.

UNITED STATES PATENT OFFICE.

WALTER H. DIFFENDALL, OF HAGERSTOWN, MARYLAND.

MACHINE FOR HOLDING RIVETS DURING UPSETTING.

1,247,380.

Specification of Letters Patent. Patented Nov. 20, 1917.

Application filed March 23, 1917. Serial No. 153,038.

To all whom it may concern:

Be it known that I, WALTER H. DIFFENDALL, a citizen of the United States, residing at Hagerstown, in the county of Washington and State of Maryland, have invented certain new and useful Improvements in Machines for Holding Rivets During Upsetting; and I hereby declare that the following is a full, clear, and exact description thereof, reference being had to the accompanying drawings, which form part of this specification.

This invention is a novel machine especially designed for use in riveting the back flue sheet or fire box sheet of boilers in place; but useful in other places where it is necessary to hold rivet heads during the operation of upsetting the ends of their shanks.

The object of this invention is to provide a novel machine having a "dolly bar" or holding on bar, which can be readily adjusted to engage the die head of the dolly bar with the head of the rivet, and then can apply a constant pressure to the dolly bar sufficient to hold the rivet-head firmly in place during the upsetting of the shank of the rivet by hammering.

I will describe one embodiment of the invention as illustrated in the accompanying drawings to enable others to understand and use the same; but the invention does not reside in the specific form or construction of parts illustrated in said drawings, as such embodiment of the invention is capable of modification and change while retaining the essential features of the invention; and therefore the features and combinations of parts for which protection is desired are summarized in the claims following such description.

In the drawings:

Figure 1 is a side elevation of a machine embodying the invention, applied to the back flue head of a boiler with the dolly bar in position to hold a rivet.

Fig. 2 is a front view of the machine removed.

Fig. 3 is a lower end view of the machine.

Fig. 4 is an enlarged vertical sectional view on line 3—3 Fig. 1.

The machine shown has a "dolly bar", or holding on bar 1 having one end 1^a bent approximately at right angles to the main body thereof and forming a die head pref-

erably provided in its inner side with one or more die-sinks 1^b each adapted to fit the head of a rivet. The other end portion of the dolly bar is preferably formed into a yoke 1^c.

A fluid pressure cylinder 2 is preferably disposed within the yoke of the dolly-bar and in axial alinement with the body of the said bar. Said cylinder 2 may be attached at one end in any suitable manner, (as by means of a stud bolt 2^a and nut 3^a) to an arm of a bracket or abutment 3 of any suitable kind, which can be fastened to a stable support when the machine is in use.

The bracket 3 may be detachably attached to the back-flue-head S of a boiler by any suitable means. As shown it is secured by means of a bolt 4 passed through one of the flue holes in the head. Said bolt has a head 4^b slightly smaller in diameter than the flue-holes in the head S and has a shoulder 4^a next the head smaller than the head and shorter than the thickness of the sheet, and said bolt has a reduced threaded shank 4^c engaging an opening in the bracket 3 as shown, and adapted to be engaged by a nut 4^e, to detachably fasten the bracket to the flue-head as shown in Fig. 1. This bolt can be readily engaged with any flue hole from the outside of the sheet, and the bracket 3 can be tightly clamped to the flue sheet at any desired point.

Within the cylinder 2 is a piston 5 slidably fitted therein and which may be provided with suitable packing rings 5^a to prevent leakage of fluid.

A ring 6 is preferably screwed into the lower end of cylinder 2 as shown in Fig. 4, to guide the piston 5 in its movement and prevent the piston 5 falling out of the cylinder when adjustments are being made.

To the outer end of piston 5 is preferably detachably attached a guide member which in the construction shown has a shank 7, a body 7^a and a pin 7^b. The shank 7 of said member enters an opening in the reduced outer end of the piston; the body 7^a is interposed between the piston and the outer end of bar 1^c of the yoke; and the pin 7^b passes through an opening in the end bar 1^c of the yoke and guides the piston relatively to the yoke, and enables the yoke and piston to be readily engaged or disengaged. The body 7^a has an annular groove 7^c which is engaged by spring fingers 9^a attached to a

retaining ring 9 engaging a groove 5^c in the outer end of the piston. Said guide member 7^b serves to keep the dolly-bar 1 in line with piston 5 when the parts are in operative position.

Washers 8 may be strung on pin 7^b between the body 7^a and the end bar to vary the normal distance between the die head 1^a of the dolly bar and the cylinder when the 10 machine is in working position.

Compressed air or other actuating fluid may be admitted into the cylinder 2 between the piston 5 and the closed end of the cylinder through a port 5^e when it is desired 15 to force the piston out of the cylinder. Such fluid may be supplied by a pipe 10 connected to any suitable supply of fluid under pressure; said pipe having a suitable controlling valve.

20

Operation.

In using the machine for riveting back flue head sheets to boilers as indicated in Fig. 1 the bracket 3 is first detachably attached to 25 the back flue head by means of bolt 4 as indicated in Fig. 1. The lower end bar 1^e of the yoke of the dolly bar is then engaged with the pin 7^b and the die head or end 1^a of the dolly-bar is hooked over the top sheet. 30 A rivet is then put in place, and the head 1^a shifted to engage one of the dies 1^b with the rivet head. Fluid is then admitted into the cylinder so as to move the piston outward (and thus force the dolly-bar downward,) or in a direction away from the head 1^a, thus putting great pressure upon the rivet-head and holding the same securely while the inner end of its shank is being 35 swaged. When the machine is in place as 40 shown in Fig. 1 the dolly bar can be shifted to either side to engage a succession of rivets without having to relocate the bracket after each operation.

The machine can be operated in any position; the dolly bar can be quickly shifted from one position to another to engage different rivets in different sections of the seam or seams within its range. Preferably the head 1^a of the dolly bar has two dies 1^b; 45 but can be provided with as many dies as is necessary to have one or the other reach rivets in different portions of the seam. For use on an ordinary locomotive boiler two dies in the head would be sufficient.

55 The machine can be used to hold rivets where the rivet head cannot be seen by the operator; and by its use, many rivets necessary to complete such seams perfectly, can be properly fastened, that could not be done 60 by any other dolly. The machine can also be used in water-legs by bolting bracket 3 through staybolt holes.

The machine saves time and labor; the riveting operation can be performed more 65 quickly and in a more workmanlike manner

than is possible with the usual method of holding a die by hand tools.

What I claim is:

1. In combination a bar having a part adapted to engage a rivet head; a cylinder; 70 a piston in the cylinder, means detachably connecting the said piston with the said bar, means for detachably fastening the cylinder to a support fixed relatively to the rivet to be headed, and means for admitting fluid 75 into the cylinder whereby the piston is ejected and the bar moved to firmly hold the rivet head.

2. A machine for the purpose specified comprising a bar having one end bent at 80 right angles and provided with a die sink to engage a rivet, a piston connected with said bar, a cylinder adapted to be engaged by the piston, means for detachably attaching said cylinder to a support fixed relative 85 to said bar, and means for admitting fluid into said cylinder.

3. A machine for the purpose specified comprising a cylinder, means for detachably attaching said cylinder to a support, a bar 90 having one end bent at right angles to engage a rivet, a piston in said cylinder, a member connected with said bar, means detachably connecting said member with the piston, and means for admitting fluid into 95 said cylinder.

4. A machine for the purpose specified comprising a bar having one end adapted to engage a rivet head and its other end provided with an opening; a cylinder, means for detachably attaching said cylinder to a support fixed relatively to the rivet, a piston in said cylinder, a member engaging the piston and having a pin engaging the opening in the end of the bar, and means for 105 admitting fluid into said cylinder.

5. A machine for the purpose specified comprising a bar having one end bent at right angles to engage a rivet head and its other end formed into a yoke, a cylinder 110 adapted to be located within the yoke, means for detachably attaching said cylinder to a support fixed relatively to the rivet, a piston in said cylinder, a member having a portion engaging the piston and another engaging the yoke, means detachably connecting said member with the piston, and means for admitting fluid into said cylinder. 115

6. A machine for the purpose specified comprising a bar having one end bent at right angles and provided with a die sink to engage a rivet, and its other end having a yoke provided with an opening in its end; a cylinder adapted to be located within the yoke, means for detachably attaching said cylinder to a support fixed relatively to the rivet, a piston in said cylinder, a member having a portion engaging the piston and a pin engaging the opening in the end of the yoke, means detachably connecting said 120 125 130

member with the piston, and means for admitting fluid into the cylinder.

7. In combination, a bar having a part adapted to engage a rivet head; a cylinder; 5 a piston in the cylinder, means connecting the said piston with the said bar; means for fastening the cylinder to a support fixed

relatively to the rivet to be headed, and means for admitting fluid into the cylinder whereby the piston is ejected and the bar 10 caused to firmly hold the rivet head.

In testimony that I claim the foregoing as my own, I affix my signature.

WALTER H. DIFFENDALL.
